UNITED STATES PATENT OFFICE.

FRANCIS M. BOOKWALTER, OF SPRINGFIELD, OHIO.

DESIGN FOR A HURDY-GURDY WATER-WHEEL.

SPECIFICATION forming part of Design No. 26,774, dated March 16, 1897.

Application filed March 27, 1895. Serial No. 543,404. Term of patent 7 years.

To all whom it may concern:

Be it known that I, FRANCIS M. BOOKWALTER, a citizen of the United States, residing at Springfield, in the county of Clark and State of Ohio, have invented a certain new and original Design for Hurdy-Gurdy Water-Wheels, of which the following is a specification, reference being had therein to the accompanying drawings.

My invention consists in a new and original design for a hurdy-gurdy water-wheel.

In the accompanying drawings, in which like reference-letters indicate corresponding parts, Figure 1 is a perspective view of a water-wheel embodying my design; Fig. 2, a cross-section of the rim looking into the interior of the buckets, and Fig. 3 a section lengthwise of the rim and through one of the buckets looking into the remaining part sidewise.

The leading feature of my design consists of the buckets set in two series, one alternating in position with the other, with the ridge standing between the two series.

A is the hub, B the spokes, and C, D, and E the tripart rim, being curved at F where the part C unites with the parts D and E.

G are the buckets, which have two outer sides II and I and two inner sides formed by the parts of the rim. The interior of the buckets constitutes a concavity without angles, the various surfaces being blended one into the other by curves, as shown. The buckets also have bottoms J, which are curved, as shown. Thus the rim has a central annular ridge, and the buckets are set in two series, one alternating in position with the other, with the ridge standing between the two series. 30 35

Having thus fully described my invention, what I claim as new, and desire to secure by Letters Patent, is—

The design for a hurdy-gurdy water-wheel herein shown and described.

In testimony whereof I affix my signature in presence of two witnesses.

FRANCIS M. BOOKWALTER.
